[57] CLAIM

The ornamental design for a paper dispenser, as shown and described.

DESCRIPTION

FIG. 1 is a bottom, front, and right side perspective view of a paper dispenser showing my new design; FIG. 2 is a top, front, and left side perspective view thereof;

FIG. 3 is a top, front, and right side perspective view thereof, with the casing being shown pivoted to an open position;

FIG. 4 is a top, front, and left side perspective view of the wall-mounting plate portion thereof, with the casing omitted for clarity of illustration;

FIG. 5 is a top, rear, and right side perspective view of the wall-mounting portion thereof, with the casing omitted for clarity of illustration; and,

FIG. 6 is a bottom, front and left side perspective view of the casing portion thereof, with the wall-mounting portion omitted for clarity of illustration.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 337,679
DATED : July 27, 1993
INVENTOR(S) : Giorgetto Giugiaro

It is certified that error appears in the above-identified patent and that said Letters Patent is hereby corrected as shown below:

On the Title page, under item [19], "Guigiaro" should read --Giugiaro--.
item [75], "Inventor" should read --Giorgetto Giugiaro--.

Signed and Sealed this
Fifth Day of April, 1994
